UNITED STATES PATENT OFFICE.

FRANK P. SHEPARD, OF EDMOND, OKLAHOMA TERRITORY, ASSIGNOR TO THE OLIVER TYPEWRITER COMPANY, OF CHICAGO, ILLINOIS, A CORPORATION OF ILLINOIS.

TYPE-WRITER.

No. 821,263.

Specification of Letters Patent.

Patented May 22, 1906.

Application filed December 15, 1904. Serial No. 236,974.

To all whom it may concern:

Be it known that I, FRANK P. SHEPARD, a citizen of the United States, residing at Edmond, in the county of Oklahoma, Oklahoma Territory, have invented certain new and useful Improvements in Type-Writers; and I do hereby declare that the following is a full, clear, and exact description thereof, reference being had to the accompanying drawings, and to the numerals of reference marked thereon, which form a part of this specification.

This invention pertains to the class of type-writers having a shift-key or shift-keys for shifting the platen to different positions for writing capital letters or other characters.

Preparatory to writing any letter or character requiring the shifting of the platen in a type-writing machine of this class the shift-key is depressed, and it is held in depressed position during the full operation of writing the letter or character, thus requiring the use of one of the fingers for this purpose and interfering with the use of the other fingers of the same hand for writing.

The shift-key is commonly placed in and forms a part of the regular bank of keys of the machine; but owing to the weight and consequent inertia of the platen and its attached parts and the non-elastic operative connection between said platen and shift-key the latter has an action much heavier than that of the other keys. Since the shift-key is usually operated by the fourth or weakest finger of the hand, it is always annoying to operators having delicate or weak fingers, while, on the other hand, persons with stronger fingers, knowing the heavy action of the shift-key, will attack it with too great force and throw the platen and its supporting parts with injurious force against the stops that limit the shifting movement of said platen.

The objects of the invention are to overcome the difficulties above named; and it consists in the matters hereinafter described, and pointed out in the appended claims.

For carrying out the objects stated simple and inexpensive means have been provided by which the platen at each time that it is shifted from normal position is automatically locked in its shifted position and an operative connection is arranged between the lock-

ing mechanism and the space-key and type-keys, whereby the stroke of said space-key or a type-key following the actuation of a shift-key will release the locking mechanism and allow the platen to return to normal position in obedience to springs or other means usually employed for the purpose. By this construction and arrangement of the parts it is only necessary when beginning a new sentence or paragraph to depress the shift-key to its full depth, after which the finger may be removed from it and all of the fingers will be free to operate the keys. After writing the first letter or character of the sentence the platen is released, as aforesaid, and returns to its normal position more quickly than it could if its release had to be accomplished by removing the finger from the shift-key. As an additional means of providing the shift-key with an action or touch more nearly like that of the type-keys the operative connection between said shift-key and the parts which it shifts is made elastic, thus allowing the shift-key to be partially or fully depressed without movement of the platen and allowing the platen to complete its shifting movement as quickly as its inertia can be overcome by the elastic connection.

A type-writing machine containing the improvements described is shown by the accompanying drawings, in which—

Figure 1 is a vertical section of one of the type-writers in common use, taken on a line extending from front to rear of the machine near the center thereof. Fig. 2 is a side elevation of an elastic connecting device applied between the shift-key and the shifting frame which carries the paper-carriage and platen. Figs. 3 and 4 are views of the forward end of said connecting device, showing changed positions of the parts thereof. Fig. 5 is a perspective view of the two shift-keys used on the machine shown, together with the associated parts. Fig. 6 is a perspective view of the locking-bar-releasing plunger shown in Fig. 5. Fig. 7 is a perspective view of the guide-plate shown in Fig. 5. Fig. 8 is a perspective view of the supporting-bracket for the guide-plate. Fig. 9 is a detail central section taken through said releasing plunger, guide-plate, and supporting-bracket. Fig. 10 is a detail plan section of the same parts, taken on line 10-10 of Fig. 9.

Referring to the said drawings, the machine shown therein has a base portion 1, a shifting frame 2, supporting carriage-tracks 3, a carriage 4, supported by said tracks and carrying a platen 5, type-bars 6, key-levers 7, operatively connected with said type-bars 6, a universal bar 8, which is depressed at each stroke of any key-lever, and a space-key 9, attached to a space-key lever 10. A rock-shaft 11 is mounted horizontally in the base 1 under the free ends of the type-key levers 7 and extending transversely thereof. Said rock-shaft has an upwardly-extending rigid arm 12, operatively connected with the shifting frame 2 by means hereinafter described. Two shift-keys 13 and 14 are shown, which have connection with said rock-shaft. Two helical springs 15 and 16 are applied between the base 1 and the shift-keys for returning said shift-keys and the parts upon which they act to normal position. The universal bar 8 forms one side of a substantially rectangular frame 17, which is mounted pivotally on the base 1 by pivots located at 18. The space-key lever 10 is operatively connected with said frame 17 by a hooked bolt 19, so that at each stroke of said space-key 9 said universal bar 8 is depressed in the same manner as by the type-key levers 7.

In place of the rigid connecting-rod heretofore employed to afford the necessary connection between the arm 12 of the rock-shaft 11 and the shifting frame 2 for the platen and carriage the connecting-rod shown in Fig. 2 is employed. Said rod has at its forward end an eye which engages the stud 21 of the rock-shaft arm 12 and at its rear end an eye 22, engaging a screw-stud 23, inserted in the shifting frame 2. This rod consists of a main portion 24, in the bifurcated end of which is pivoted a bell-crank lever 25 by a transverse horizontal pivot-pin, the longer depending arm of said lever 25 extending approximately at right angles to the portion 24 of the connecting-rod when in normal position. The shorter horizontal arm 26 rests between the free ends of two leaf-springs 27 and 28, which are secured to the upper and lower faces of the portion 24. Said springs act to yieldingly hold said member 25 in its normal position with its depending arm 25 at right angles to the main part 24, and thereby normally holds the parts in position to maintain a normal distance between the eyes 20 and 22, which constitutes the effective length of the connecting-rod.

Either one of the shift-keys 13 or 14 may be depressed to its full depth instantly without waiting for the shifting frame 2 and the carriage and platen which it supports to complete their movement, the elastic connecting-rod assuming one of the positions shown in Figs. 3 and 4 against the force of one of the springs 27 and 28 and then drawing the shifting frame and attached parts

into shifted position as quickly as their inertia can be overcome.

The mechanism for locking the platen in shifted position embraces features as follows: The rock-shaft 11 is provided with a rigid downwardly-extending arm 29, and the lower end of said arm is attached pivotally to a horizontal rearwardly-extending locking-bar 30, whose free end rests and slides in a guide-plate 32, attached to a depending bracket 31, bolted to the under side of the base 1. The said plate 32 extends below the lower part of the bracket 31, and said plate has in its lower part a slot 33 to loosely receive the bar 30, said plate 32 being arranged vertically and secured to the bracket 31 by the two screws 34. The locking-bar 30 is drawn or pressed upwardly against the upper side of the slot 33 by means of a helical spring 35, which is attached to said bar near its forward end and is hooked over the axis portion 18 of the frame 17. Said bar 30 is provided near its free end with forwardly and rearwardly facing locking-shoulders 36 and 37, adapted to engage the plate 32 at the top of the slot 33 when the bar is thrown to the forward or rearward limit of its endwise movement. An unlocking-plunger 38, which is shown separately by Fig. 6, is hung pivotally between two lugs 39 upon the under side of the universal bar 8. The lower end of said plunger is bifurcated, and its prongs slide on the front and rear faces of the guide-plate. Said guide-plate has at its upper edge a guide-slot 40, which receives the lower end of the plunger and holds the lower end of the same from lateral movement. The forward face of the bracket 31 is vertically grooved to form a recess behind the guide-plate 32, in which the rear prong of the plunger 38 may freely move.

When one of the shift-keys is depressed and revolves the rock-shaft 11 for shifting the platen, the arm 29 moves the locking-bar 30 endwise in the slot 33 until one of the shoulders 36 or 37 is lifted into engagement with the plate 32 in obedience to the tension of the spring 35. Then at the first following depression of the space-bar or one of the type-keys the universal bar 8 is depressed, and with it the plunger 38, the lower end of which strikes the bar 30 and releases the shoulder thereof from its locking engagement with the plate 32. The shifting-frame and plates then return to normal position under the action of one of the helical springs 15 and 16.

Although the locking-bar 30 is released from its locking engagement on the downward movement or stroke of the type-keys and the platen is thus released for returning to its normal position before the printing stroke of the type occurs, owing to the high speed that the type has gained at the time the release occurs and the slow movement of the platen in starting to return, the type will

strike in the proper position and will form a printed line having no noticeable errors in alinement. The use of the parts described does not interfere in any way with the operation of the levers, hooks, or other devices heretofore used upon like machines for locking the shift-keys down when desired.

The main portion 24 of the connecting-rod and the bell-crank lever 25 thereof constitute, in effect, two pivotally-connected members which are held yieldingly in angular relation to each other by a spring or springs, so that the effective length of the connecting-rod may be changed or varied by movement of the outer ends thereof toward or from each other, and inasmuch as such yielding construction in the connecting-rod may be produced without the employment of the bell-crank lever 25 as one part or member of said rod, but will be produced when said rod consists of two pivotally-joined members which are held by a spring or springs yieldingly in angular relation, I do not wish to be limited to the use of a bell-crank lever as one member of said rod except so far as the same may be herein specifically claimed as a separate and distinct improvement.

With respect to the automatic locking means for holding the shifting frame temporarily in its shifted position it will be observed that what has hereinbefore been called the "guide-plate" 32 constitutes, in effect, a stationary locking member which coacts with the locking-bar 30 and that said stationary locking member need not necessarily have the form of a guide-plate, which also acts as a guide for the plunger 38; but said locking member may be variously arranged in practice so that it may properly coact with said locking-bar, and a suitable guide or guiding means for the lower end of the plunger 38 may also be variously formed or arranged without departure from my invention.

I am acquainted with the mechanism shown in Letters Patent No. 504,713 by which the shift-key is locked down at each depression and released by the following stroke of a type-key or the space-key; but the mechanism shown in said patent must be adjusted to lock exactly at the time that the platen completes its shifting movement, else it will fail to lock or will lock too soon and allow the platen to drop back slightly toward normal position, where it will not receive the impression of the type in the proper place to form a printed line in perfect alinement. To avoid the necessity of accurate adjustment of the locking parts and as a means of giving to the shift-key an action or touch more nearly like that of the type-keys and keeping the platen from being thrown violently against the stops that limit its shifting movement, I provide an elastic operative connection between said platen and a movable actuating

member (the rock-shaft 11 of the drawings) which is operated by the shift-key and connects the platen-locking device with said movable actuating member, thus allowing the shift-key to be instantly and fully depressed and the locking of the movable actuating member to take place without regard to the movement of the shifting frame, which latter is allowed to complete its shifting movement as soon as its inertia can be overcome by the elastic connection, which may be after the movable actuating member has been shifted and locked in its shifted position.

I claim as my invention—

1. In a type-writer, the combination with a platen, key-levers, a shifting frame and a shift-key, of a movable actuating member which is operated by the shift-key, an elastic connection between said movable actuating member and the shifting frame, means for locking the said movable actuating member in its shifted position, and means operated by the key-levers for releasing the said movable actuating member and permitting the same, together with the shifting frame, to return to their normal positions.

2. In a type-writer, the combination with a platen, key-levers, a universal bar, a shifting frame and a shift-key, of a movable actuating member which is operated by the shift-key, an elastic connection between said movable actuating member and the shifting frame, locking means for holding the said movable actuating member in its shifted position, and means operated by the universal bar for releasing the said movable actuating member.

3. In a type-writer, the combination with a platen, key-levers, a universal bar, a shifting frame and a shift-key, of a movable actuating member which is operated by the shift-key, an elastic connection between said movable actuating member and the shifting frame, locking means for the said movable actuating member embracing an endwise-moving locking-bar which is connected and moves with the said movable actuating member and is provided with a locking-shoulder, a stationary locking member coacting with said bar, a spring acting on the locking member to throw it into its locking position, and a releasing member connected with the universal bar and acting on the locking member to release the same.

4. In a type-writer, the combination with a platen, key-levers, a universal bar, a shifting frame and a shift-key, of a movable actuating member which is operated by the shift-key, an elastic connection between said movable actuating member and the shifting frame, a horizontally-arranged locking-bar which is connected and moved with the said movable actuating member, said locking-bar being provided with a locking-shoulder, a stationary locking member coacting with

said locking-bar, a lifting-spring acting on said bar to throw its shoulder into engagement with the locking member, and a releasing-plunger connected and moving with the 5 universal bar and which acts on the locking-bar to depress the same and release its locking-shoulder from said locking member.

5. In a type-writer, the combination with a platen, key-levers, a universal bar, a shifting frame and a shift-key, of a rock-shaft which is turned by the shift-key and is provided with a rigid arm having elastic connection with said shifting frame, locking means for said rocking shaft embracing a rigid arm 10 on said shaft, a locking-bar pivoted to said arm and provided with a locking-shoulder, a stationary locking member coacting with said locking-bar, a spring acting on the locking-bar to effect engagement of the locking-shoulder thereon with said locking member, and a releasing-plunger connected and moving with the universal bar and acting on said locking-bar to release the same from said stationary locking member. 15
- 20 6. In a type-writer, the combination with a platen, a shifting frame, and a shift-key, of a connection between the said shift-key and the shifting frame embracing an endwise expansible and contractible connecting-rod consisting of two pivotally-connected members arranged in angular relation to each other, and a spring applied to yieldingly hold the outer ends of said members at a certain distance apart, whereby the effective length of 25 the connecting-rod may be changed by the yielding of said spring.

7. In a type-writer, the combination with a platen, a shifting frame adapted to move in opposite directions from its normal position 40 and two shift-keys, of a connection between the said shift-keys and the shifting frame embracing an endwise expansible and contractible connecting-rod consisting of two pivotally-connected members arranged in angular relation to each other, and two springs ap- 45

plied to yieldingly hold the outer ends of said members from spreading apart or moving toward each other, whereby the effective length of the connecting-rod may be increased or decreased by the yielding of one or the 50 other of said springs.

8. In a type-writer, the combination with a platen, a shifting frame and a shift-key, of a connection between said shift-key and the shifting frame embracing an endwise expansible and contractible connecting-rod consisting of two pivotally-connected members one of which has the form of a bell-crank lever, and a spring applied to one of said members and acting on one arm of the bell-crank lever to yieldingly hold the other arm of said bell-crank lever in a certain angular relation to the other member, whereby the effective length of the connecting-rod may be changed by the yielding of said spring. 65

9. In a type-writer, the combination with a platen, a shifting frame, and a shift-key, of a connection between the shift-key and shifting frame embracing an endwise expansible and contractible connecting-bar consisting of 70 two pivotally-connected members one of which has the form of a bell-crank lever having one of its arms normally at an angle to the other member and its other arm parallel therewith and two flat springs acting on the 75 opposite sides of the parallel arm of the bell-crank lever to yieldingly hold the other arm of said bell-crank lever in a certain angular relation to the other member of said rod, whereby the effective length of said rod may 80 be increased by the yielding of one or the other of said springs.

In testimony that I claim the foregoing as my invention I affix my signature, in presence of two witnesses, this 21st day of November, A. D. 1904.

FRANK P. SHEPARD.
